(57) **CLAIM**

The ornamental design of a protective case component, substantially as shown and described.

DESCRIPTION

FIG. 1 is a top front perspective view of a protective case component in accordance with the present design;

FIG. 2 is a top view thereof;

FIG. 3 is a right side view thereof;

FIG. 4 is a bottom view thereof;

FIG. 5 is a left side view thereof;

FIG. 6 is a front view thereof; and,

FIG. 7 is a back view thereof.

The broken lines in the Figures show portions of the protective case component which form no part of the claimed design.
